UNITED STATES PATENT OFFICE.

HUBERT TOLER, OF SWEETWATER, TEXAS.

SAFETY MEDICINE-SPOON.

1,390,475.

Specification of Letters Patent. Patented Sept. 13, 1921.

Application filed May 24, 1920. Serial No. 383,864.

To all whom it may concern:

Be it known that I, HUBERT TOLER, a citizen of the United States, residing at Sweetwater, in the county of Nolan and State of Texas, have invented new and useful Improvements in Safety Medicine-Spoons, of which the following is a specification.

This invention relates to improvements in medicine spoons, and more particularly to a type of the same adapted for the purpose of administering medicine.

The primary object of the invention is to provide for a comparatively simple and inexpensive construction of the character mentioned, and one provided with a means whereby the spoon may be carried for a distance, as from a table or cabinet in a room to the bed of a patient, after the same has been filled, or partly filled, in safety, and without possible loss of the contents, or part thereof.

Another object of the invention is to provide a spoon of the type mentioned and one of a nature particularly adapted for use in hospitals and the like for the administering of medicine to infants or weak, bed-ridden patients, means being provided for the confining of the medicine in the spoon until after the same has been inserted into the mouth of the person being dosed, and in a manner to eliminate the necessity of unduly disturbing the patient, and, consequently, reducing the chance of loss or spilling of the medicine to a minimum.

A further object of the invention is to provide for a spoon of the type specified, and one which is so constructed as to be readily cleansed, disinfected, and kept in a sanitary condition at all times.

With the foregoing and other objects in view, the invention resides in the certain novel construction as will be hereinafter more fully described, set forth in the appended claims, and illustrated in the accompanying drawing, in which:

Figure 1 is a side elevation,

Fig. 2 is a top plan, and

Fig. 3 is a vertical longitudinal section on the line 3-3 of Fig. 2.

Referring to the drawing, in which similar characters of reference designate corresponding parts in the several views thereof, the numeral 10 indicates the bowl portion of the spoon and 11 the handle portion thereof, the bowl being of any desired size

and shape as may correspond with either of the usual forms of common tea-spoons, dessert-spoons or table-spoons.

Conforming to the shape of the bowl 10 is a substantially flat cover plate 12 arranged to snugly contact the edge of the bowl in a manner to preclude all possible escape of even the thinnest of liquids from the latter when in closed position. The material of which the spoon is made is recessed, to provide a shoulder, as at 13, at the junction of the bowl 10 with the handle portion 11, so that the horizontal wall of the shoulder is continuous with the top edge of the bowl and provides for a supporting surface for the cover plate 12 to further prevent the escape of any of the liquid contents at this point.

A two-part hinge is provided for pivotally mounting the cover plate 12 in position 75 on the bowl 10, and one part of this hinge, as at 14, is permanently secured on the adjacent handle portion immediately in rear of the recess 13, while the other portion of the hinge, as at 15, is permanently secured 80 to the cover plate 12 and has its connecting portion projecting rearwardly of the latter and is secured in engagement with the portion 14 by means of a removable pin or 85 pintle 16.

An operating handle 17 is provided for actuating the cover plate 12 to and from closed position, and the same is provided with a depending leg portion 18 having a 90 foot portion 19 which is secured permanently to the cover plate 12 immediately in advance of the hinge portion 15. The handle 17 extends rearwardly from its point of connection with the cover plate 12 in alignment with respect to the handle portion 95 11 of the spoon, and spaced above the latter for a desired distance for the proper opening and closing of the cover plate 12.

For maintaining the cover plate 12 in normally closed position and firmly in contact with the top edge of the bowl 10, a coiled spring 20 is positioned between the handle portion 11, of the spoon, and the operating handle 17, of the cover plate 12, and preferably at a point immediately in 100 rear of the hinge, or, as shown, the lower end of the coiled spring is held in position, in any desired or suitable manner, on the hinge portion 14. The upper end of the coiled spring 20 is retained in position 105 110

against the underside of the handle 17 by means of oppositely depending ears or lugs 21 formed with the latter.

In the use of the spoon thus provided, 5 and especially for the dosing of infants or weak and bed-ridden persons, medicine is placed in the bowl 10, and the cover plate 12 closed thereover, so that the spoon may be transported from a table or medicine 10 cabinet in the sickroom to the patient without spilling the contents. Without undue disturbance of the patient, or even should the patient be sleeping or in a comatose or semi-comatose state, the spoon is inserted between the lips, or between the teeth and the handle 11 and the handle 17 are then pressed together, against the tension of the coiled spring 20, and the medicine allowed 15 to pass into the mouth of the patient. In this use and operation of the spoon, the opening movement of the bowl 10 and the cover plate 12 tends to force the jaws of the patient apart and hold the same in position to assure of the entire dose of medicine being discharged well into the mouth 20 of the patient.

For the proper cleansing and disinfecting of the spoon, the pin or pintle 16 may be removed to allow the separation of the 25 hinge members 14 and 15, one from the other, and, consequently, the removal of the cover plate 12 and its handle 17 from the

bowl 10 and its handle portion 11, whereby the parts may be thoroughly washed and dried for subsequent use.

35

It is to be understood that, while specific terms of construction and arrangement of parts have been used throughout the foregoing description of the invention, various changes and modification in detail may be 40 resorted to without departing from the spirit and scope of the latter.

Having thus fully described the invention, what I claim, is:—

In a medicine spoon, the combination 45 with a bowl portion and a handle portion therefor, of a snugly fitting cover plate normally closing said bowl portion and having an operating handle overlying the handle portion of the spoon, a shoulder formed at 50 the juncture of the bowl portion and the handle portion thereof and having its horizontal wall continuous with the top edge of the bowl portion to provide a supporting surface for the cover plate at this point, 55 a removable pin hingedly securing said cover plate and its operating handle in position, and a coiled spring disposed between the operating handle of said cover plate and the handle portion of the spoon 60 for holding the former in normally closed position on the latter.

In testimony whereof I affix my signature.
HUBERT TOLER.
